UNITED STATES PATENT OFFICE

2,541,269

WATCHMAKER'S MILLING MACHINE

Cecil T. Mitchell, Corpus Christi, Tex., assignor of
one-third to James J. Thomas and one-third to
Earnest Anderson, Corpus Christi, Tex.

Application September 26, 1947, Serial No. 776,356

4 Claims. (Cl. 82—14)

1

This invention relates to a machine for duplicating and forming small articles, such as watch parts or the like.

An object of this invention is to provide a machine in the form of a small milling machine which will permit the formation of the various parts of a watch from a sample part, the newly formed part being produced with very close precision.

Another object of this invention is to provide a machine of this kind which can be mounted on any bench, or other plane surface and will quickly and accurately cut the work piece to the desired configuration.

A further object of this invention is to provide a machine of this kind which includes interchangeable or positionable parts so that the sample holding chuck can be adapted to meet varying conditions.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a detailed side elevation of a device constructed according to an embodiment of this invention.

Figure 2 is a fragmentary plan view of the device.

Figure 3 is a sectional view taken on the line 3—3 of Figure 1.

Figure 4 is a fragmentary sectional view taken on the line 4—4 of Figure 2.

Figure 5 is a fragmentary sectional view taken on the line 5—5 of Figure 1.

Figure 6 is a fragmentary sectional view taken on the line 6—6 of Figure 2.

Figure 7 is a fragmentary sectional view taken on the line 7—7 of Figure 2.

Figure 8 is a fragmentary plan view showing the mounting of several attachments on the device.

Figure 9 is a sectional view taken on the line 9—9 of Figure 8.

Figure 10 is a sectional view taken on the line 10—10 of Figure 8.

Referring to the drawings, the numeral 15 designates generally a frame or base which is formed of opposite end members 11 and 12, the end member 11 having rubber feet 13 secured to an out-

2

wardly projecting flange 14. The end member 12 has rubber feet 15 mounted on the lower end thereof. The end members 11 and 12 are connected together by a pair of connecting bars 16 which hold the end members 11 and 12 in upright position.

A motor 17 is mounted on a bracket 18 which extends upwardly from the flange 14 and the motor 17 has a driving pulley 19 in a lowermost position. The end member 12 has mounted on the upper end thereof an inwardly projecting right-angular table 20 which provides a support for a rotary chuck generally designated as 21. The chuck 21 is mounted in a bearing sleeve 22 formed with an upper annular flange 23 engaging on the upper side of the table 20 and the bearing sleeve 22 is secured against rotation by means of a set screw or other fastening means 24. The table 20 is also split or slotted as indicated at 25 and a clamping screw 26 extends across the slot 25 and co-acts with the set screw 24 in firmly locking the bearing sleeve 22 in the table 20.

The chuck 21 includes a sleeve 27 which is rotatable within the bearing member 22 and the lower end of the sleeve 27 has a groove pulley 28 thereon about which a driving belt 29 engages. The belt 29 is also trained about the driving pulley 19 rotated by the motor 17. The sleeve 27 has mounted on the upper end thereof a jaw contracting head 30 which is larger in diameter than the diameter of the sleeve 27 and rotatably engages on the upper side of the flange 23. The jaw contracting head 30 is formed with a tapered bore 31 within which a plurality of tapered jaws 32 engage. The jaws 32 are carried by a threaded shaft or stem 33 which is threaded into the sleeve 27 and the shaft or stem 33 has mounted on the lower end thereof a knurled wheel 34 which is disposed below the sleeve 27.

40 A stationary chuck, generally designated as 35, is also carried by the table 20 at one side of the chuck 21. The stationary chuck 35 is adapted to hold a sample article in a position whereby the sample may be duplicated as will be herein-after described. The chuck 35 includes a sleeve 36 which extends through the table 20 and is tightly secured relative thereto by means of a set screw 37. The chuck 25 also includes a jaw contracting head 38 which is formed with a tapered bore 39 within which work clamping jaws 40 engage. The head 38 forms a shoulder 41 at the lower end thereof which engages on the upper side of the table 20. The jaws 40 have extending downwardly therefrom a threaded adjusting or

jaw operating shaft 42 on which a knurled wheel 43 is secured below the sleeve 36.

A vertically adjustable tool holding table, generally designated as 44, is formed with a vertical front side 45 having a dovetail channel 46 within which a dovetail key 47 carried by the end member 12 slidably engages. The table 44 also includes a horizontal upper side 48 which is disposed in parallel relation to the table 20. The table 44 is adapted to be locked in vertically adjusted position by means of a shim 49 which is interposed in the dovetail channel 46 and is clamped against the tongue 47 by means of a pair of locking screws 50 on which lock nuts 51 are threadably mounted.

The table 44 is adapted to be vertically adjusted with precision by means of a micrometer adjusting member 52 which engages a threaded shaft 53 fixed relative to the stationary table 20. The micrometer table adjusting member 52 is disposed in a vertical position and extends above the horizontal table member 48. The table 48 is formed with a pair of openings 54 and 55 through which the chuck members 21 and 35, respectively, are adapted to project.

A tool carriage generally designated as 56 is slidably and adjustably mounted on the horizontal table member 48 and includes a base plate 57 formed with a dovetail tongue 58 engaging in a dovetail guide channel 59 formed in the table member 48. The channel 59 is disposed substantially centrally between the two openings 54 and 55 and extends to the outer end of the table. The carriage 56 includes a transversely extending tool rest or rib 60 which is formed with a pair of channels 61 and 62 within which a pair of tools 63 and 64, respectively, are adapted to engage. A clamping bar 65 engages over the tools 63 and 64 and is tightly secured relative to the rib 60 by means of a pair of bar securing members 66. The tool 63 is a cutting tool and is disposed in a position to intersect the vertical axis of the chuck 21. The tool 64 is a follower tool and is disposed in a position to intersect the vertical axis of the stationary chuck 35.

The carriage 56 is adjusted lengthwise of the guide 59 by means of a threaded adjusting screw 67 which is threaded into a block 68 carried by the rear portion of the carriage 56. A screw clamping bar 69 is secured to the block 68 by fastening members 70 and is adapted when in tight position to lock the screw 67 against rotation. This bar 69 may also be adjusted relative to the block 68 so as to eliminate any end play between the screw 67 and the block 68. The screw 67 rotatably engages through an upstanding lug 71 carried by a supporting block 72 which is secured to the vertical side 45 of the table 44 by means of a bolt 73 and a nut 74. The screw 67 is adapted to be rotated by means of a micrometer operator 75 of conventional construction which extends endwise from the lug 71. The micrometer member 75 includes a vernier adjusting member 76 extending from the end of the coarse or rough adjusting portion 77 thereof. In this manner the carriage 56 may be adjusted with precision as to the sample which is carried by the fixed chuck 35 and the cutting tool 63 will be moved inwardly and adjusted to very close dimensions.

Referring now to Figures 8 to 10, inclusive, in certain instances it is desirable that the sample article be disposed in depending position above the table 48. The chuck 35 is removed from the table 20 and is then disposed in an inverted posi-

tion above the table 48. A vertically disposed supporting post 78 is mounted in an opening 79 formed in the table 48 and fixed in vertically adjusted position and in circumferentially adjusted position by means of a set screw 80.

A horizontally disposed bracket arm 81 is mounted in an opening 82 formed in the post 78 being endwise and circumferentially adjusted by means of a set screw 83. The arm 81 is formed with an annulus or head 84 at its inner end through which the sleeve 36 of the chuck 35 engages and the sleeve 36 is vertically adjusted in the annulus 84 by means of set screw 85.

Where it is desired to use an engraver or hand cutting tool for cutting the work piece carried by the chuck 21, a tool rest 86 is disposed above the table 48 and at one side of the chuck 21. The rest 86 is formed with a shank or arm 87 which engages through an opening 88 formed in a vertical supporting post 89. The supporting post 89 extends through an opening 90 formed in the table 48 and a set screw 91 locks the post 89 in vertically adjusted position and in circumferentially adjusted position. The shank 88 is fixed in endwise adjusted position by means of a set screw 92 which is threaded into the upper portion of the supporting post 89.

In the use and operation of this device the work piece is clamped into the chuck 21 and is disposed in extending position above the table 44. The motor 17 is connected with the source of electric power so that the chuck 21 carrying the work piece will be rotated at the desired rate. The sample work which is to be duplicated is clamped into the chuck 35. The carriage 56 is adjusted horizontally and the table or vertically movable carriage 44 is vertically adjusted by the vernier adjusting means 52. The tool 64 is a blunt tool which is adapted to engage the sample work, whereas the tool 63 is a cutting tool which will cut the work piece as the vertically and horizontally movable carriages are adjusted.

With a device of this kind exceedingly small articles such as are used in or form parts of watches may be accurately and quickly duplicated and the finished work piece will be precision made so that it will accurately fit into the watch or the like in the same manner as the original article.

I claim:

1. A duplicating machine comprising a base frame, a power member carried by said frame, an inverted L-shaped stationary table fixed to said frame and having one side thereof vertical and the other side thereof horizontal, a vertically disposed rotary chuck carried by the horizontal side of said table, a stationary chuck carried by said table in spaced parallel relation with respect to said rotary chuck, a vertically movable inverted L-shaped carriage carried by the vertical side of said table and having a horizontal side overlying the horizontal side of said stationary table and formed with a pair of openings axially aligning with said chucks, a driving connection between said rotary chuck and said power member, a tool carriage slidably carried by the horizontal side of said first carriage, means securing a pair of tools on said tool carriage, threaded means vertically adjusting said first named carriage, and threaded means horizontally adjusting said tool carriage.

2. A duplicating machine comprising a base frame formed of upright end members, connecting bars fixed between said end members, a power member carried by one end member, a horizontal

inwardly projecting plate carried by the other end member, a rotary chuck carried by said plate having the axis thereof vertical, a driving connection between said chuck and said power member, a second chuck fixedly carried by said plate in spaced parallel relation with respect to said rotary chuck, a vertically movable carriage slidably carried by said other end member, means vertically adjusting said carriage, said carriage including a horizontal table overlying said plate and formed with a pair of openings coaxial with said chucks, a tool carriage slidable on said horizontal table, means adjusting said tool carriage relative to said openings, and means clamping a pair of tools on said tool carriage, one of said tools constituting a cutting tool and the other tool constituting a follower tool.

3. A duplicating machine comprising a base frame formed of upright end members, connecting bars fixed between said end members, a power member carried by one end member, a horizontal inwardly projecting plate carried by the other end member, a rotary chuck carried by said plate having the axis thereof vertical, a driving connection between said chuck and said power member, a second chuck fixedly carried by said plate in spaced parallel relation with respect to said rotary chuck, a vertically movable carriage slidably carried by said other end member, threaded means vertically adjusting said carriage, said carriage including a horizontal table overlying said plate and formed with a pair of openings coaxial with said chucks, a tool carriage slidable on said horizontal table, threaded means adjusting said tool carriage relative to said openings, said tool carriage adjusting means including a nut carried by said tool carriage, and a threaded adjusting bolt rotatably carried by said first named carriage, and means clamping a pair of tools on said tool carriage,

10

20

25

40

one of said tools constituting a cutting tool and the other tool constituting a follower tool.

4. A duplicating machine comprising a base frame formed of upright end members, connecting bars fixed between said end members, a power member carried by one end member, a horizontal inwardly projecting plate carried by the other end member, a rotary chuck carried by said plate having the axis thereof vertical, a driving connection between said chuck and said power member, a second chuck fixedly carried by said plate in spaced parallel relation with respect to said rotary chuck, a vertically movable carriage slidably carried by said other end member, means vertically adjusting said carriage, means locking said carriage in vertically adjusted position, said carriage including a horizontal table overlying said plate and formed with a pair of openings coaxial with said chucks, a tool carriage slidable on said horizontal table, means adjusting said tool carriage relative to said openings, and means clamping a pair of tools on said tool carriage, one of said tools constituting a cutting tool and the other tool constituting a follower tool.
